? Assignor to,
the Tucker Manufacturing Company of same place
Letters Patent No. 2432. Date Sept. 25. 1866.
Design for a Pulley Hall Lamp.

The schedule referred to in these Letters Patent and making part of the same.

To all whom it may concern:

Be it known that I, F. J. Tucker of Boston
in the County of Suffolk and State of Massachusetts have originated
and produced a new Design for a Pulley Hall lamp of which
the following is a full and clear description, reference being had
to the accompanying drawing making part of this specification.

In this Design which is for a swinging lamp, the drawing
represents chains a, a, running over sheaves b, and having suspended
upon them a collar c, which fits upon the glass shade d,
and the base or lamp and shade seat e.

I claim, and wish to secure by Letters Patent,
the Design for the ornamental base and collar as shown and described.
